UNITED STATES PATENT OFFICE

2,482,799

DRY CONTACT TYPE ELECTRICALLY
ASYMMETRIC DEVICE

Edward Arthur Richards and Leslie James Elliss,
son, London, England, assignors to Interna-
tional Standard Electric Corporation, New
York, N. Y.

Application December 13, 1946, Serial No. 716,158
In Great Britain December 21, 1945

1 Claim. (Cl. 175—366)

1

This invention relates to the construction of electrically asymmetric devices such as rectifiers, photo-electric cells and thermo-couples of the dry contact type and more particularly to the construction of elements for such purposes which comprise a base plate, coated with a layer of semi-conductor such as selenium, to which is applied a counter-electrode.

One conventional form of element consists in a plate having a hole through which an insulated mounting rod is passed to enable contacts and terminals to be clamped to the electrodes of the element. In another conventional form the element is placed in a container, terminals on the outside thereof leading through the container to arrangements inside which make the necessary contacts with the electrodes of the element.

One object of the invention is to provide a unit plate type element which is readily connected into a circuit or is readily connected to another such element.

Another object of the invention consists in providing an element having an easily and accurately regulated working area, free from contact or assembly pressure, with terminals of simple construction. Yet another object of the invention is to provide an element which can be used singly or in bridge or other assemblies.

According to one feature of the present invention a dry contact type electrically asymmetric element comprises two electrodes and terminals for said electrodes affixed outside the working area.

According to another feature of the invention a dry contact type electrically asymmetric element comprises a base plate having an area larger than the active area of the element, a semi-conductor layer covering said base plate area, a layer of insulating material defining said active area, and holes in said base plate and said layers, through which terminals are affixed, one of said terminals having electrical connection with said base plate and another of said terminals having electrical connection with a counter electrode which extends over said active area.

According to yet another feature of the invention the terminals of such an element are symmetrically positioned while the counter electrode is unsymmetrically positioned with relation to the working area.

The invention is particularly applicable where it is desired that the element shall be compact and easily mounted or suspended by its connections and have a relatively small working area

2

as in radio and communication equipments and circuits.

The invention will be better understood from the following detailed description, taken in conjunction with the accompanying drawings in which—

Figures 1 and 2 show a plan view and sectional elevation respectively of a selenium rectifier element embodying the invention:

10 Figures 3 and 4 are similar views of another embodiment of the invention; and

Figure 5 shows a plan view of an assembly of elements forming a full wave rectifier.

In Figures 1 and 2, 1 represents a base plate 15 on which a layer of semi-conducting material 2, e. g. selenium is applied by any well known method. A layer of insulating material 3, consisting of paint, lacquer, paper or any suitable material which can be caused to adhere to the 20 surface of the semi-conductor, covers the surface of the layer 2, leaving exposed the working surface 11. 4 is a layer of counter-electrode material, covering the surface 11 and having an extension 12 towards one end of the element. The 25 layers 1, 2, 3 contain two holes 13, 14 which can be made at any suitable stage in the manufacture of the element, through which pass tubular extensions 6 and 9 of two terminals 5 and 8 respectively. Terminal 8 makes contact with the 30 counter-electrode metal extension 12 and is insulated from the base plate 1 by an insulating bush 10 through which the extension 9 passes. The end of extension 9 is bent, swaged or spun over the outside of bush 10 and a washer 15 to 35 secure the terminal 8 and bush 10 in position. At the hole 13 terminal 5 is similarly secured but with an insulating bush 16 inserted for the topside, the terminal making contact with base plate 1 through washer 1. In Figures 3 and 4 the insulating layer 3 only extends around the 40 hole 14 and the working area is controlled by limiting the area of the counter-electrode 4 by masking or other suitable means. Terminal 8 is secured as before, making contact with extension 12 of the counter-electrode over the insulating layer 3. Terminal 5 is insulated from the selenium surface by insulating washer 16 45 and is secured as before.

Instead of providing the terminals with tubular extensions, the terminals may be affixed by solid rivets insulated in the same way.

Elements of the kind described can be assembled to form a full wave rectifier as shown in plan view, Figure 5. Four elements laid together as 55 shown and firmly fixed together through their

holes by soft rivets 17 make the necessary contacts with one another and, through the rivets, form the well known bridge circuit of a full wave rectifier. Unwanted terminal tags may be cut off.

Other arrangements of assembly can be devised by those skilled in the art to meet special circuit and equipment requirements. The rigid fixing of the terminals enables an element to be suspended in circuit thereby without other support and in fact to carry the weight of other small parts which are sometimes used in radio and other circuits.

While the invention has been described in relation to a rectangular element with rounded ends as shown in the drawings, its application is not limited to such a shape and an element may be of any desired suitable shape. Moreover, the terminals may be at the same edge or at adjacent edges of the element without exceeding the scope of the invention.

What is claimed is:

A dry contact type electrically asymmetric element that comprises: an elongate flat metallic base element having a pair of openings formed therein, one being located near each end thereof; a layer of semi-conductive material overlying the top surface of said base element; an electrically insulative coating covering the exposed top surface of the semi-conductive layer with the exception of a relatively small localized area spaced from and located intermediate the openings formed in the base element; a counter-electrode on said insulative coating, positioned around marginal portions of a first but not the second of said pair of openings in the base element and

25

30

35

making contact with the semi-conductive layer throughout the exposed localized area not covered by the insulative coating; a pair of electrically insulative sleeves, each having a flange integrally formed on one end thereof, positioned within and extending through said openings in a manner such that the flange of the sleeve in the said first opening overlies a portion of the bottom surface of the base element at the margin of the opening, and the flange of the sleeve in the said second opening overlies a portion of the insulative coating on the semi-conductive layer at the margin of the opening; a pair of rivet elements having radially extending lugs formed integrally with the heads thereof, within said insulative sleeves, the ends of said rivets remote from the heads being provided with metallic washers and being bent over said washers whereby the rivet in the first opening is electrically connected with the counter-electrode and the rivet in the second opening is connected with the base element.
